ROTARY FILE

Clarence O. Olson, Chicago, Ill., assignor to Spin-Dex, Inc., Chicago, Ill., a corporation of Illinois

Application May 7, 1947, Serial No. 746,481

10 Claims. (Cl. 45—3)

1

This invention relates to rotary index files wherein a drum with file compartments spaced around its periphery is rotatable to bring any selected compartment into a position where access may be had to the contents thereof.

An object of the invention is to provide novel means to retain the contents of the various file compartments against displacement when such compartments are rotated away from the position wherein the contents thereof are customarily withdrawn or inserted.

A further object is to provide a rotary file of the aforesaid character in which are embodied various improvements to minimize wear and replacement of the movable parts and afford greater ease of operation.

Specifically, it is an object of this invention to provide a rotary card file having retaining devices for the contents of the file compartments which normally are urged inwardly to closed positions and which are so arranged that the retaining means for each file compartment is withdrawn positively by a cam or equivalent means when the compartment is disposed in file-transfer position for extraction or insertion of its contents.

The above and various other objects, advantages and features of the invention will be apparent from the following specification when taken in connection with the accompanying drawings wherein a certain preferred embodiment is set forth for purposes of illustration.

In the drawings, wherein like reference numerals refer to like parts throughout:

Fig. 1 is a perspective view of a rotary file constructed in accordance with and embodying the principles of the invention;

Fig. 2 is a vertical sectional view of the apparatus;

Fig. 3 is a vertical section on the line 3—3 in Fig. 2;

Fig. 4 is a fragmentary view showing, in elevation, a file retaining device and the cam for operating this device when a file compartment is in file-transfer position;

Fig. 5 is a horizontal section on the line 5—5 in Fig. 3; and

Fig. 6 is a vertical section on the line 6—6 in Fig. 4.

Referring to the drawings, the file cabinet 10 includes a rotary frame or drum 12 mounted on a shaft 14 that is carried by the cabinet 10. The drum 12 carries a series of filing compartments 16 which are disposed around the periphery of the drum. The flat top 18 of the cabinet 10 has

2

a rectangular opening therein through which access may be had to the contents of a compartment 16 disposed in file-transfer position. The drum 12 may be rotated by a wheel 20 which is disposed outside of the cabinet 10 and mounted on the shaft 14, thereby to bring any selected compartment 16 into the aforesaid transfer position at which the contents of the compartment may be inserted or extracted.

The filing compartments 16, as they approach the transfer position, project slightly above the top 18. Arcuate flanges or rails 22 disposed on either side of the opening in the top 18 serve as guides for a lid or cover 24, Fig. 2, that may be slid into or out of position for closing the aperture. The cover 24 may be secured by a lock 26 when the filing cabinet is not in use.

In accordance with the invention, each of the filing compartments 16 is provided with a pair of retaining devices 28 which are secured to the outer faces of the drum 12 in any suitable manner on either side of the compartment 16. These retainers 28 are in the form of flat, wing-like members of yieldable material such as sheet metal, preferably having inherent resiliency and normally tending to lie against the outer surfaces of the drum 12. The upper ends of the retainers 28 are bent inwardly to afford lips or flanges 30 which are adapted to overhang the cards, folders or other files in the compartment 16 when the retainers 28 are occupying their normal positions. The lips 30 prevent the contents of the compartment 16 from falling out or being otherwise displaced when the compartments 16 are rotated from file-transfer position. It will be understood that the retainers 28 may also be merely flexible or pivoted on the drum 12 and urged inwardly by separate spring members if desired.

When the filing compartments 16 are rotated into the file-transfer position, it is necessary that the retainers 28 be moved outwardly from the drum 12 to withdraw the lips 30 into their open positions as shown in Figs. 3, 5 and 6. For this purpose I have provided a pair of circular cam members 32 which are stationarily supported by the frame of the cabinet 10 on either side of the drum 12. Each of the retainers 28 is provided with an ear, bracket or lug 34 that is hooked behind and rides on a circular flange of the adjacent cam 32. Each cam 32 is of such configuration that the retainers 28 are pulled outwardly when the filing compartment 16 is approaching, occupying or receding from the file-transfer position as shown in Figs. 3 and 5. Each cam 32 is

relieved as indicated at 36 in the vicinity of the file-transfer position to afford clearance for the retainers 28 when they are in their open positions. At all other times in the course of travel of the compartment 16 the retainers 28 are permitted to flex inwardly by the cams 32, thereby bringing the lips 30 into closed position wherein they are effective to engage the upper edges of the cards or other files in the compartment and retain these files against displacement.

My invention has the advantage that the retainers 28 are subjected to positive camming action only when the associated compartments 16 are in or near the file-transfer position. At all other times the retainers 28 are held inwardly by their own resiliency and may ride loosely on the cams 32. The file contents are securely held against displacement by the retainers 28 when they are in their closed positions. The file cabinet is mounted on casters so that it may readily be positioned with the drum-operating wheel 20 on either the right or left-hand side facing the operator.

It is obvious that various changes may be made in the specific embodiment set forth for purposes of illustration without departing from the principles of the invention. The invention is accordingly not to be limited to the precise details disclosed herein but includes all modifications thereof within the spirit and scope of the appended claims.

The invention is hereby claimed as follows:

1. A rotary file comprising a rotatable drum formed with a series of filing compartments arranged around the periphery thereof, stationary means defining a file-transfer position with respect to said drum, a series of file retainers carried by said drum and respectively associated with said compartments, each of said retainers including resilient means normally urging the retainer into a closed position, and stationary cam means constantly cooperating with said retainers but bearing thereon only proximate to said file-transfer position to move each retainer into its open position as the respective filing compartment is disposed in file-transfer position.

2. A rotary file comprising a rotatable drum formed with a series of filing compartments arranged around the periphery thereof, stationary means defining a file-transfer position with respect to said drum, a series of file retainers carried by said drum and respectively associated with said compartments, each of said retainers being yieldable and normally occupying a closed position in contact only with said drum to retain the files in the respective compartment, and stationary cam means cooperating with said retainers but bearing thereon only proximate to said file-transfer position whereby each retainer is positively actuated into its open position as the respective filing compartment is disposed in file-transfer position.

3. A rotary file comprising a rotatable drum formed with a series of filing compartments arranged around the periphery thereof, stationary means defining a file-transfer position with respect to said drum, a series of file retainers carried by said drum, each of said retainers being resilient and normally occupying a closed position by virtue of their resiliency to retain the files in the respective compartment, and stationary cam means cooperating with said retainers whereby each retainer is positively actuated into its open position as the respective filing compartment is disposed in file-transfer position.

4. A rotary file comprising a rotatable drum formed with a series of filing compartments arranged around the periphery thereof, stationary means defining a file-transfer position with respect to said drum, a series of file retainers carried by said drum on either side thereof and respectively associated with said compartments, each of said retainers including a yieldable member having a hook-like portion extending therefrom, and stationary cam means cooperating with said retainers to positively move each retainer from the closed position which it normally occupies into its open position as the respective filing compartment is disposed in file-transfer position, said cam means including annular cam members received by the hooked portions of said retainers.

5. A rotary file comprising a support, a shaft carried by said support, a rotatable drum mounted on said shaft formed with a series of filing compartments arranged around the periphery thereof, stationary means on said support defining a file-transfer position with respect to said drum, a series of file retainers secured to and carried by said drum on either side thereof, each of said retainers including a flat resilient member normally tending to lie against a face of the drum and provided with a lateral hook-shaped portion and being bent at its outer end to afford a lip which is effective to retain the files in the respective filing compartment when the retainer is disposed inwardly against said drum, and stationary cam means on said support comprising annular cam members concentric with said shaft on either side of said drum, said annular cam members being at all times received by the hooked portions of said file retainers but bearing thereon only proximate to said file-transfer position and being formed to draw the retainers outwardly whereby the lips thereof clear the filing compartments as the respective compartments are disposed in file-transfer position and permitting return of the retainers to their normal inward positions when the respective filing compartments are disposed away from the file-transfer position.

6. A rotary card file comprising a housing having a service opening, a rotatable drum journaled in the housing and having a circumferentially-arranged series of peripheral card compartments of which a number are accessible by way of said opening at any position to which the drum is rotated, a series of radially-arranged plates with inner portions carried by the drum end walls and outer portions yieldably held to the latter and formed with bends over the entrances to said compartments to bar the exit of cards therefrom, and means to retract the outer portions of such plates as occur opposite said opening, whereby to cause the bends of such plates to clear the compartment entrances opposite the same, the outer plate portions and bends returning to their original positions when carried beyond said means by the rotation of the drum.

7. A rotary card file comprising a housing having a service opening, a rotatable drum journaled in the housing and having a circumferentially-arranged series of peripheral card compartments of which a number are accessible by way of said opening at any position to which the drum is rotated, a series of radially-arranged plates with inner portions carried by the drum end walls and outer portions yieldably held to the latter and formed with bends over the entrances to said compartments to bar the exit of cards therefrom.

and means to retract the outer portions of such plates as occur opposite said opening, whereby to cause the bends of such plates to clear the compartment entrances opposite the same, the outer plate portions and bends returning to their original positions when carried beyond said means by the rotation of the drum, said means comprising stationary units carried inside the walls of the housing which are opposite said end walls, and elements carried by said plates and cooperative with said units.

8. A rotary card file comprising a housing having a service opening, a rotatably journaled drum within the housing, said drum having end walls and a circumferentially-arranged series of peripheral card compartments of which a number are accessible by way of said opening at any position to which the drum is rotated, a series of radially-arranged plates with inner portions carried by the drum end walls and outer portions yieldably held to the latter and formed with bends over the entrances to said compartments to bar the exit of cards therefrom, and means to retract the outer portions of such plates as occur opposite said opening, whereby to cause the bends of such plates to clear the compartment entrances opposite the same, the outer plate portions and bends returning to their original positions when carried beyond said means by the rotation of the drum.

9. A rotary card file comprising a housing having a service opening, a rotatably journaled drum within the housing, said drum having end walls and a circumferentially-arranged series of peripheral card compartments of which a number are accessible by way of said opening at any position to which the drum is rotated, a series of radially-arranged plates with inner portions carried by the drum end walls and outer portions yieldably held to the latter and formed with bends over the entrances to said compartments to bar the exit of cards therefrom, and means to retract the outer portions of such plates as occur opposite said opening, whereby to cause the bends of such plates to clear the compartment entrances

45

opposite the same, the outer plate portions and bends returning to their original positions when carried beyond said means by the rotation of the drum, said means comprising stationary units disposed inside the walls of the housing which are opposite said end walls, and elements carried by said plates and cooperative with said units.

10. A rotary card file comprising a housing having a service opening, a rotatably journaled drum within the housing, said drum having a pair of end walls and a circumferentially-arranged series of peripheral card compartments therebetween of which a number are accessible by way of said opening at any position to which the drum is rotated, a series of radially-arranged plates with inner portions carried by the drum end walls and outer portions yieldably held to the latter by the resiliency of the plates, said plates being formed with bends over the entrances to said compartments to bar the exit of cards therefrom, and means to retract the outer portions of such plates as occur opposite said opening, whereby to cause the bends of such plates to clear the compartment entrances opposite the same, the outer plate portions and bends returning to their original positions when carried beyond said means by the rotation of the drum, said means comprising a hook-like bracket carried by each plate, and a pair of stationary cams disposed inside the walls of the housing adjacent the respective drum end walls, the brackets being engageable with the cams to flex the plates against their resiliency.
